Application May 30, 1945, Serial No. 596,755

22 Claims. (Cl. 250—27)

1

My invention relates to electron discharge devices and associated circuits and more particularly to electron discharge devices of the kind utilizing a beam of electrons which is periodically deflected, and circuit means for automatically maintaining the beam centered.

One type of conventional beam deflection tube described and claimed in my United States Patent No. 2,294,659 assigned to the same assignee as the present application includes an elongated envelope having at one end a cathode for providing a stream of electrons and at the other an output electrode for receiving said electrons. The beam of electrons on leaving the cathode passes through an accelerating and beam forming electrode assembly sometimes referred to as the aperture assembly and between a pair of deflecting electrodes, the beam being focused on an intercepting wire by the electrostatic field between the aperture assembly and the deflecting electrodes which form an electron lens. Alternating voltage applied to the deflecting electrodes will cause periodic deflection of the beam across the intercepting wire to the output electrode. In normal operation the incoming signal and local oscillator voltages are impressed simultaneously across the deflection electrodes usually by means of a high frequency resonant line circuit. An intermediate frequency transformer is connected to the output electrode. Best mixer operation requires the beam to be accurately centered on the intercepting wire. This is done by a bias voltage applied to the deflecting electrodes.

It has been found that with this type of tube the most critical operating voltage is the beam centering bias. It has also been found that tubes which have the best signal-to-noise ratio are usually the most critical to adjust. As a result, it has been necessary to provide a front of panel bias control on equipment using this type of tube so that small changes in voltage or small changes in tube characteristics during the life would not cause too much drop in performance. The adjustment ordinarily must be made with an actual signal present since the anode current does not vary enough to permit the best operating point to be found by using a meter in the anode.

It is therefore the principal object of my invention to provide an electron discharge device of the beam deflection type in which the most critical operating voltage can be maintained automatically at substantially the correct value. More specifically, it is an object of my invention to provide an electron discharge device of the beam deflection type and an associated circuit

2

in which the beam is automatically properly centered.

The novel features which I believe to be characteristic of my invention are set forth with particularity in the appended claims, but the invention itself will best be understood by reference to the following description taken in connection with the accompanying drawing in which Figure 1 is a schematic diagram showing a beam deflection tube of the kind under consideration and its associated circuit. Figures 2 and 3 are graphs showing output characteristics of a properly centered beam and an improperly centered beam. Figure 4 is a schematic diagram of one form of device made according to my invention and its associated circuit for maintaining the beam properly centered. Figures 5 and 6 are graphs showing transconductance characteristics of a tube of the type shown in Figure 1 with the beam properly centered and with the beam improperly centered. Figure 7 is a schematic diagram of an electron discharge device of the type shown in Figure 1 and a modified circuit made according to my invention for maintaining the beam automatically centered. Figure 8 shows a series of curves showing operation of the device and circuit shown in Figure 7. Figure 9 is a modification of the arrangement shown in Figure 7. Figure 10 is a graph showing operation of the tube and circuit of Figure 9. Figure 11 is a still further modification of the tube and circuit shown in Figure 7. Figure 12 is a graph showing the operation of the tube and circuit shown in Figure 11. Figures 13 and 14 are still further modifications of a tube and circuit made in accordance with my invention.

Referring to Figure 1 of the drawings, the usual beam deflection tube used as a mixer in superheterodyne reception includes an elongated envelope 10 having at one end the indirectly heated cathode 11 and at the other a collector or anode 12. Positioned next adjacent the cathode is the aperture assembly and accelerator through which the electrons are directed and which with the deflecting electrodes 14 and 15 provide a lens action for focusing the beam on the intercepting electrode 16. A secondary electron suppressor 17 is positioned between the interceptor 16 and the anode 12. An alternating voltage is applied to the deflecting electrodes 14 and 15 by means of the input circuit 18 to which both the input signal voltage and the local oscillator voltage may be applied. The intermediate frequency output transformer 19 is connected to the output electrode 12. The deflecting volt-

age causes the beam to be periodically deflected across the intercepter electrode 16 so that the tube has the characteristic shown in Figure 2. With no voltage applied to deflecting electrodes the beam is directed on the intercepting electrode 16 so that no current passes to the output electrode as shown by the solid line curve 1. Deflection of the beam to either side of the intercepting electrode 16 causes the output current to rise when local oscillator voltage is applied. The average current is that shown by the dotted line 2. The minimum in each case appears at the correct mixer bias indicated. From the graph it is clear that correct centering is approximately at the minimum of the anode current curve although this minimum is rather broad. A slightly misaligned tube will give a slightly misplaced minimum as shown in Figure 3.

Because a correctly centered beam in a well aligned tube passes the same current on one side of the intercepting wire as on the other, this feature may be used to provide automatic centering with a tube with its associated circuit and in which automatic centering may be had is shown in Figure 4. Like numbers apply to like elements in all of the figures. The tube in Figure 4 differs from that shown in Figure 1 by being provided with a split output electrode comprising the elements 12' and 12''. Each of these elements is connected to a separate primary 22 and 23 of the intermediate frequency transformer having a secondary 24. By-pass condensers 27 and 28 are also provided. The secondary of the input transformer 20 is split and isolated for different D.-C. biasing potentials on electrodes 14 and 15 by means of the condenser 21. Separate biasing potentials are applied from the biasing voltage source to the electrodes 14 and 15 through the resistors 25 and 26 which may be manually adjusted.

When the beam is properly centered so that the deflection is equal on both sides of the intercepting electrode 16, the current flowing through each of the resistors 25 and 26 is the same so that the drop across these resistors is the same and no relative change of bias is made on the deflecting electrodes. If, however, the beam is off-center, more current will flow through one resistor than the other thus changing the voltage drops and the biasing voltages. For example, if the beam is off-center upwardly in Figure 4, increased average current will flow on the average to the output electrode element 12' than that to output electrode element 12'' causing a greater drop in resistor 26 than in resistor 25, thus decreasing the positive bias on electrode 14 with respect to that on electrode 15 on which the positive bias is increased due to decreased average current flowing through resistor 25. This has the tendency to shift the beam back toward deflecting electrode 15 so that the mean positive of the beam is again substantially along a line between the cathode and the intercepting electrode 16 so that substantially equal deflections are again produced about the mean path.

A disadvantage of the arrangement just described is that a special tube construction is required which increases the difficulty of manufacture since it involves the lining-up of a second pair of electrodes, 12' and 12'' with the intercepting wire 16. Furthermore, the method employed involves chiefly current changes so that with an unsymmetrical current characteristic the centering may not be exactly correct for best mixer

operations which depends upon the transconductance rather than the current.

Referring to Figure 5 which shows the transconductance characteristic with and without oscillator voltage applied, it is seen that the transconductance, that is the slope of the curves shown in Figure 2, is positive on one side of the correct centering and negative on the other. A centering system which operates by searching for the point of zero transconductance overcomes the disadvantages listed above and eliminates the necessity for a special tube. It has the further advantage that the tube characteristic which also chiefly determines mixer operation, that is the transconductance, is the one which is used to correct the centering. In Figure 5 is shown the curves of transconductance plotted against centering bias for the typical tube whose anode current curves are shown in Figure 2. It is seen that when optimum local oscillator is applied, the average transconductance passes through zero, the correct centering point, with a very high slope thereby providing very accurate centering when this method is utilized.

One means of deriving automatic centering voltage from the transconductance characteristic requires the application of an auxiliary A.-C. voltage to the deflection plates. The fundamental component of the A.-C. output anode current which results from an A.-C. input is zero when the tube is centered, that is, when the transconductance passes through zero and reverse in phase through this point with equal changes of transconductance in the positive and negative directions. A phase-responsive rectifier operating from the A.-C. anode current will supply a direct current of one polarity when the centering is off on one side and will supply a direct current of an opposite polarity when the centering is off on the other side. This is the action which is needed for incorrect centering.

In Figure 7 I show a tube and a circuit made according to my invention which utilizes the transconductance characteristic for providing automatic centering of the beam. In this arrangement the bias is provided for deflecting electrodes 14 and 15 through the resistors 26' or 25' and I apply a local oscillator voltage by means of the local oscillator 27. Connected in output of the tube is a feedback circuit 28 tuned to the local oscillator frequency. In this arrangement the local oscillator voltage is used as the alternating current source for the centering control and the beam deflection tube is utilized as a phase-responsive rectifier. When the beam is properly centered, a current having a second harmonic of the local oscillator frequency is generated and there is no fundamental component of local oscillator frequency in the anode circuit, thus circuit 28 which is tuned to the fundamental frequency does not respond to the current in the output circuit. This circuit 28 discriminating against the strong second harmonic component and having no voltage across it feeds nothing back to the signal input circuit to which it is coupled. As a result, the normal D.-C. anode current flows through resistors 25' and 26' which are arranged to provide deflection plate D.-C. bias. Adjustment of 26' permits this bias to be varied in either direction. If, now the beam centering is slightly off, that is, toward the upper side of the intercepting electrode 16, there will be a local oscillator frequency component in the anode current which is fed back through the circuit 28. With the phase adjustment correctly

made, this fed back component will aid the normal local oscillator voltage and slightly increase the anode current. As a result, the D.-C. drop across the resistors 25' and 26' will increase, thus decreasing the voltage on electrode 14 and causing the beam to be shifted downwardly and so correcting the centering. On the other hand, if the beam has been slightly off toward the lower side of the wire, the local oscillator frequency component in the anode current again appears but in opposite phase. Thus the anode feedback would also be opposite in phase and would buck the normal local oscillator voltage. This decreases the anode current and reduces the direct current voltage drop across 25' and 26' making electrode 14 more positive so as to deflect the beam upward toward the center, thereby again correcting any off-center tendency. To explain in more detail the action which takes place, reference is had to Figure 8. In the upper left-hand portion of Figure 8 is shown the output anode current characteristic and directly below this the voltage induced in the secondary of the transformer 20 by the local oscillator and the feedback circuit when the beam is properly centered. With the local oscillator voltage applied, the output current is a form shown by the solid line and marked 2nd harmonic I output normal." The result is an average current $I_{R_1+R_2}$ marked "Normal." If the beam shifts upwardly so that it is off-center and, as shown by the dotted line, "Shift up" under the output anode current characteristic, the output current takes the form shown by the dotted line marked, "Shift up." As a result, there is a component of output current having a fundamental frequency corresponding to the local oscillator frequency. The local oscillator circuit 28 which is tuned to this fundamental frequency then has a voltage induced across it as indicated by the curve E_A marked "Shift up." This induces a current in the secondary of transformer 20 in phase with the local oscillator voltage and the resultant is shown as E induced resultant "Shift up." This then causes an increase in the output current as indicated by the "Shift up" average current curve $I_{R_1+R_2}$, causing a drop in voltage across resistors 25' and 26' and a shift down of the beam. On the other hand, if the shift of the beam off-center is down, a resultant voltage is generated in circuit 28 corresponding to the voltage curve marked "Shift down." It is observed that the shift is 180° with respect to the shift up of the beam. Under these conditions, the voltage induced by the circuit 28 and the local oscillator 27 in the secondary of the input transformer 20 buck each other causing a reduced induced voltage as shown by the lowermost curves. As a result, the average current in the output decreases, the voltage drop across the resistors decreases, and the resultant biasing voltage on electrode 14 rises causing the beam to be shifted upward toward the electrode 14.

If an auxiliary small A.-C. is applied to the mixer input using some frequency remote from the normal signal intermediate frequency or local oscillator frequency, it is also possible to apply automatic centering in a straight-forward manner with a separate phase-responsive rectifier. In order not to interfere with normal operation 70 the auxiliary A.-C. input must be small. Sufficient automatic control is then obtained by a high rectifier sensitivity. A phase-responsive rectifier circuit suitable for use for this purpose is disclosed in my Patent 2,054,125 assigned to

the same assignee as the present application. Rectifiers of the kind described in the patent are essentially mixers which operate with the local oscillator at exactly the same frequency as 5 the A.-C. input giving a zero frequency, that is, a D.-C. output whose polarity depends on the phase of the A.-C. input with respect to the fixed phase local oscillations.

An automatic centering control using the high 10 sensitivity phase-responsive rectifier is shown in Figure 9. In this arrangement a transformer T_1 having two secondaries 32 and 33 is utilized for applying a small A.-C. potential to the deflecting electrodes 14 and 15 and for also providing 15 the higher voltage which must be applied to the phase-responsive rectifier circuit to be described. The biasing voltage is applied from a "Focus adjustment" source through the resistor 30 the opposite ends of which are electrically connected 20 to the deflecting electrodes 14 and 15, being bypassed by condenser 21 for R.-F. currents and by condenser 31 for currents of low frequency. Connected across the resistor 30 are a pair of tubes V_1 and V_2 the grids of which are connected 25 to the secondary of transformer T_2 . The primary of transformer T_2 is connected to the output electrode 12 through the primary of the intermediate frequency transformer 19. This transformer T_2 has its primary tuned to respond 30 to the frequency of the auxiliary low frequency A.-C. applied by the transformer T_1 . An A.-C. potential is applied between the cathodes and the anodes of the tubes V_1 and V_2 by means of 35 the secondary winding 33 of the low frequency transformer T_1 .

The voltages on the anodes of the tubes V_1 and V_2 due to transformer T_1 are in phase and hence any currents flowing in the outputs are 40 normally equal and opposite so that the resultant voltages across the resistor 30 cancel out. If the grids are biased to cut-off, current will not flow unless the grids are raised to a voltage higher than cut-off voltage. If the voltage applied to the secondary of the transformer T_2 is such that the voltage of the grid of the tube V_1 increases in phase with the voltage applied to the anode, an increase in current through this tube will result, whereas under these conditions the grid of the tube V_2 is in phase opposition to the anode voltage so that the current through tube V_2 decreases if the grid is not biased to cut-off or, has no effect on this tube if the grid is biased to cut-off. Current therefore flows through resistor 30 to tube V_1 causing a drop in voltage on the upper end of resistor 30 and consequently on the deflecting electrode 14.

If the phase of the voltage in the secondary 60 of transformer T_2 is reversed so that tube V_2 becomes the conducting tube, a current will flow in the opposite direction through the resistor 30 lowering the potential at the lower end of the resistor and decreasing the potential on electrode 15. Thus the resultant rectified currents can 65 be utilized to control the bias on the deflecting electrodes.

No effect is obtained in transformer T_2 if the beam is properly centered and only the second harmonic appears in the output electrode 12. Off-centering however will cause an output current component having a frequency corresponding to the frequency of the voltage applied by transformer T_1 to electrodes 14 and 15, and depending upon the phase, either tube V_1 or V_2

will conduct to bring about a variation in the biasing voltage on the electrodes 14 or 15. The action which takes place is disclosed in greater detail in Figure 10. In the upper left-hand portion of the figure is again shown the voltage output anode current characteristic. The voltage E_{T_1} corresponding to the low frequency voltage applied by transformer T_1 to electrodes 14 and 15 when the beam is properly centered results in the output current marked "Centered normally" having a frequency twice that of the auxiliary low frequency A.-C., with the result that the voltage output through T_2 is zero since the primary is tuned only to the auxiliary low frequency A.-C. applied by T_1 . The difference between the currents of tubes V_1 and V_2 , I_{V_1} and I_{V_2} , is also zero as shown. If the beam is shifted upwardly however as indicated by the dotted line "Shift up," a current component appears in the output of the tube of a fundamental frequency which energizes T_2 "Shift up" as shown in the curve in the graphs. If properly phased, V_1 conducts so that an average bias results as indicated by $I_{V_1} - I_{V_2}$ "Shift up" causing the upper end of the resistor 30 to become less positive causing a less positive bias on electrode 14 and moving the beam back down toward the other deflecting electrode 15 to bring about proper centering. On the other hand, if the beam is shifted downwardly as indicated by "Shift down," the reverse process takes place as indicated by the "Shift down" curves shown, the average bias decreasing on electrode 15.

In beam deflection tubes of the kind described above the full output current characteristic includes two other stable points corresponding to extreme deflection of the beam to either side. Thus, in some cases, it is possible for this automatic centering circuit to give so great an output from the rectifier that operation is on one of these incorrect points. The use of transformers T_1 and T_2 adds to the cost of the equipment, and hum may be an undesirable factor in the operation of the rectifier. An improved form of circuit which minimizes these objections is shown in Figure 11. In this arrangement the voltage on the anodes is fixed while the voltage on the cathodes is an alternating voltage applied from an auxiliary low frequency A.-C. source through the transformer T_R . The tubes V_1 and V_2 may or may not be operated at cut-off. The voltage is applied to the grids through the tuned circuit 39 tuned to the auxiliary low frequency A.-C. applied to the cathode of tubes V_1 and V_2 . The low frequency A.-C. is applied to the deflecting electrodes through the circuit including resistors 37 and 38 and condenser 36 connected in the output of the tube V_2 which produces an A.-C. voltage E_{AC} across the resistor 38. Either tube V_1 or tube V_2 conducts the greatest current if the beam is off center and operation is as described above.

Referring to Figure 12, the operation of the phase-responsive rectifier circuit and the centering circuits of Figure 11 may be seen in detail. When properly centered, the normal output current having a frequency twice that of the auxiliary low frequency action appears but does not affect the input circuit 39. Shift of the beam up or down causes an output having a fundamental frequency component which excites the input circuit 39 and again if properly phased, when the beam is shifted up the current through V_1 will increase and through V_2 decrease or have

no effect on V_2 if the tube is biased to cut-off so that the relative average biases are as indicated in the graphs to again properly bias the deflecting electrodes to center the beam. If the beam is shifted down the opposite action takes place.

In some cases no auxiliary A.-C. of low frequency is readily available and it may be desirable to generate this A.-C. in the rectifier itself, by making it self-oscillating. A double triode utilizing a balanced modulator oscillator circuit has certain advantages. Such an arrangement is shown in Figure 13.

In this arrangement each of the tubes V_1 and V_2 also functions as an oscillator being provided with a feedback coil 45 and 46 for energizing the winding of T'_R connected between the cathodes. The auxiliary voltage applied to the deflecting electrodes is obtained by coupling the coil 47 to the winding of T'_R . In other respects the circuit is much the same as those previously described and functions in substantially the same manner. It is of course obvious that a double triode or pair of triodes as well as tetrodes or pentodes could be used for the tubes V_1 and V_2 .

In Figure 14 I show an arrangement wherein a single tube V_3 is utilized for bringing about automatic centering. In this arrangement the automatic centering bias resistor 30 has connected to it a second resistor 53 connected to ground for establishing a normally small bias across points 61 and 62. A separate oscillator 50 is employed for applying the auxiliary A.-C. centering voltage to the deflecting electrodes by means of the coil 51 coupled to the oscillator. A second coil 52 provides the additional A.-C. needed to operate the phase-responsive rectifier and is connected to the cathode of V_3 . Tube V_3 is thus connected to the oscillator and its plate current, in effect, flows through the upper part of the resistor 30. The resistor 53 in effect replaces the second tube used in the other arrangements. The current through the resistor 30 splits through the tube V_3 and the resistor 53 so that normal voltages across these resistors are equal and opposite. If an A.-C. voltage appears on the grid of V_3 , due to improper centering of the beam, the current in V_3 will change. When the beam is shifted up, the A.-C. on grid is out of phase with the A.-C. on the cathode so that the resultant current through the resistor 30 increases so that there is a voltage drop at the upper end of resistor 30 reducing the bias on the deflecting electrode 14 to shift the beam down again. The reverse action takes place if the beam is off-center in the opposite direction.

While I have indicated the preferred embodiments of my invention of which I am now aware and have also indicated only one specific application for which my invention may be employed, it will be apparent that my invention is by no means limited to the exact forms illustrated or the use indicated, but that many variations may be made in the particular structure used and the purpose for which it is employed without departing from the scope of my invention as set forth in the appended claims.

What I claim as new is:

- An electron discharge device having means including a cathode for directing an electron beam along a predetermined path, deflecting electrode means along the path of said electrons for periodically deflecting said electrons from said path, means for applying a biasing voltage to said

deflecting electrode means for maintaining said beam along said predetermined path when no deflecting voltage is applied to said deflecting electrode means, means for applying an alternating voltage of one frequency to said deflecting electrode means to periodically deflect said electrons, and a second means for applying an alternating voltage of a different frequency to said deflecting electrode means, and means connected to said biasing means and responsive to a deviation of the electron beam from said predetermined path as a mean position and including means responsive to said second frequency for varying the biasing voltage whereby said beam is returned to said predetermined path as a mean position.

2. An electron discharge device having means including a cathode for directing a beam of electrons along a predetermined path, deflecting electrode means along the path of said electrons for periodically deflecting said electrons from said path, and output means in the path of said electrons for receiving said electrons, means for applying a deflecting voltage to said deflecting electrode means of a given frequency, other means for applying a deflecting electrode voltage to deflecting electrode means of a different frequency, means for applying a biasing voltage to said deflecting electrode means for maintaining said beam directed along said predetermined path when no deflecting voltage is applied to said deflecting electrode means, and means responsive to the output current due to said deflecting voltage of different frequency when said beam deviates from said predetermined path as a mean position for varying the biasing voltage to return said beam to said predetermined path as a mean position.

3. An electron discharge device having a cathode for supplying a beam of electrons along a predetermined path, an output electrode positioned in the path of said electrons and a pair of deflecting electrodes positioned on opposite sides of said beam path and between said cathode and output electrode, and an intercepting electrode positioned between said cathode and output electrode and on which said beam is directed when no deflecting voltage is applied to said deflecting electrodes, means for applying an alternating voltage of one frequency to said deflecting electrodes for deflecting said electron beam across said intercepting electrode whereby an output current flows to said output electrode of a frequency twice that of said one frequency, biasing means for applying a biasing voltage to said deflecting electrodes to maintain said beam directed on said intercepting electrode when no alternating voltage is applied to said deflecting electrodes from said alternating voltage source, and means coupled between said output electrode and said biasing means and responsive to an output current of said one frequency upon deviation of the electron beam from said predetermined path as a mean position for returning said beam to said predetermined path as a mean position.

4. An electron discharge device having means including a cathode for directing an electron beam along a predetermined path, deflecting electrode means along the path of said electrons for deflecting said electrons from said path, means for applying an alternating voltage of a fundamental frequency to said deflecting electrode means for periodically deflecting said beam of electrons about said predetermined path as a mean position, and means in the path of said electrons for providing an output current of twice

the frequency of the applied deflecting voltage when said beam is properly centered along said predetermined path and an output current having a fundamental frequency component when

5 the beam is improperly centered along said predetermined path, and means coupled to the means in the path of said electrons and responsive to an output current of the fundamental frequency generated when said beam is unequally deflected.

10 about said mean position for returning said beam to said predetermined path as a mean position, to provide equal deflection about said mean position.

5. An electron discharge device having means including a cathode for directing an electron

15 beam along a predetermined path, a deflecting electrode means positioned along the path of said beam of electrons for deflecting said electrons from said path, an output electrode means for receiving said beam of electrons, means for applying

20 an alternating voltage of a fundamental frequency to said deflecting electrodes for periodically deflecting said beam of electrons on opposite sides of said predetermined path as a mean position, said output electrode means having

25 means for generating currents of only a second harmonic of said fundamental frequency when said beam is properly centered on said output electrode means and a component of the fundamental frequency when said beam is improperly

30 centered, and means connected to said output electrode means and responsive to currents of the fundamental frequency, means for applying a biasing voltage to said deflecting electrode means for centering said beam along said predetermined path, said means connected to said output electrode means responding to a fundamental frequency output when said beam is deflected unequally on opposite sides of said predetermined path, said last means varying the biasing voltage

35 40 on said deflecting electrode means to return said beam to said predetermined path as a mean position to maintain equal deflection of said beam about said predetermined path.

6. An electron discharge device having means

45 including a cathode for directing an electron beam along a predetermined path, deflecting electrodes positioned along the path of said electrons, an output electrode means for receiving said electrons, means for applying an alternating voltage

50 50 of a fundamental frequency to said deflecting electrodes for deflecting said beam of electrons about said predetermined path as a mean position, said output electrode having means for generating an output current of a harmonic frequency when said beam is equally deflected about

55 said mean position and for generating an output current having a fundamental component when said beam is unequally deflected about said mean position, means connected to the output electrode

60 65 and responsive to an output current having a fundamental frequency component for varying the applied voltage of fundamental frequency to said deflecting electrodes for varying the output current, and means responsive to the variations of said output current for varying the bias on

70 said deflecting electrodes for maintaining equal deflection of the electron beam on both sides of said predetermined path.

7. An electron discharge device having means

70 including a cathode for directing a beam of electrons along a predetermined path, an output electrode system in the path of said beam of electrons, and deflecting electrodes positioned along the path of said electrons between said cathode and said output electrode system, means for ap-

plying an alternating potential of a fundamental frequency to said deflecting electrodes, said output electrode system generating an output current having a harmonic frequency of said fundamental frequency when said beam is properly centered along said predetermined path and generating an output current having a fundamental frequency output component when said beam is deflected unequally on opposite sides of said predetermined path, means for applying a biasing voltage to said deflecting electrodes for maintaining said beam along said predetermined path when no deflecting voltage is applied to said deflecting electrodes, a phase responsive rectifier circuit associated with said biasing means, and means connected to said output electrode system and responsive to an output current having a fundamental frequency component for controlling the phase responsive rectifier circuit for varying the relative biasing voltages on said deflecting electrodes.

8. An electron discharge device having means for directing an electron beam along a predetermined path, deflecting electrodes positioned along the path of said electrons, and output electrode means for receiving said electrons, means for applying an alternating voltage of a fundamental frequency to said deflecting electrodes for deflecting said beam of electrons about said predetermined path as a mean position, said output electrode system having means for generating an output current having a harmonic frequency of said fundamental frequency when said beam is properly centered along said predetermined path and generating an output current having a fundamental frequency component when said beam is deflected unequally on opposite sides of said predetermined path, biasing means for applying a biasing voltage to said deflecting electrode, means connected to the output electrode means and including feedback means responsive to an output current of said fundamental frequency for varying the magnitude of the applied alternating voltage of fundamental frequency to said deflecting electrodes for varying the output current, and means responsive to the variations of said output current for varying the bias on said deflecting electrodes for maintaining equal deflection of the electron beam on both sides of said predetermined path.

9. An electron discharge device having a cathode for supplying a beam of electrons along a predetermined path, an output electrode positioned in the path of said electrons and a pair of deflecting electrodes positioned on opposite sides of said beam path and between said cathode and output electrode, and an intercepting electrode positioned between said cathode and output electrode and on which said beam is directed when no deflecting voltage is applied to said deflecting electrodes, means for applying an alternating voltage of one frequency to said deflecting electrodes for deflecting said electron beam across said intercepting electrode whereby an output current flows to said output electrode of a frequency twice that at said one frequency when said beam is properly centered but having a component of said fundamental frequency when said beam is off center, biasing means for applying a biasing voltage to said deflecting electrodes to maintain said beam directed on said intercepting electrode when no alternating voltage is applied to said deflecting electrodes from said alternating voltage source, and means connected between said output electrode and said biasing means and re-

sponsive to an output current of said one frequency upon deviation of the electron beam from said predetermined path as a mean position for returning said beam to said predetermined path as a mean position said last means including a phase responsive rectifier coupled to said biasing means for varying the biasing voltage applied by said biasing means to said deflecting electrodes when said beam is unequally deflected about said predetermined path as a mean position.

10. An electron discharge device having means including a cathode means for directing electrons along a predetermined path, an output electrode for receiving said electrons and an intercepting element positioned between said cathode and said output electrode, deflecting electrodes positioned along the path of said electrons and on opposite sides thereof, means for applying an alternating voltage of a fundamental frequency to said deflecting electrodes for periodically deflecting said electron beam across said intercepting element to provide an output current having a second harmonic frequency, a circuit connected to said output electrode tuned to respond to an output current of the fundamental frequency of said alternating voltage, biasing means connected between said deflecting electrodes and including a resistor, a phase responsive rectifier for applying a voltage to said resistor and including a pair of electron discharge devices having cathodes, grids, and anodes, said anodes being connected to opposite ends of said resistor, said tuned circuit being coupled to said grids, the electron discharge device having deflecting electrodes generating an output current having a fundamental frequency component when said beam is off-center, said tuned circuit responding to said fundamental output current component when said beam is off-center for causing one of said pair of electron discharge devices to conduct more current than the other for varying the biasing voltage on said resistor whereby the bias on said deflecting electrodes is varied to return said beam to a centered position.

11. An electron discharge device having means including a cathode means for directing electrons along a predetermined path, an output electrode for receiving said electrons, an interceptor element positioned between said cathode and said output electrode, deflecting electrodes positioned along the path of said electrons and on opposite sides thereof, means for applying an alternating voltage of a fundamental frequency to said deflecting electrodes for periodically deflecting said electron beam across said intercepting element, a circuit connected to said output electrode tuned to respond to an output current of the frequency of said alternating voltage, and biasing means connected between said deflecting electrodes and including a resistor, a pair of electron discharge devices having cathodes, grids, and anodes, the said anodes being connected to opposite ends of said resistor, said tuned circuit including a transformer having a secondary the opposite ends of which are connected to said grids, and means for applying an alternating voltage between said cathodes and said anodes of the frequency of said alternating voltage applied to said deflecting electrodes, said electron discharge device having deflecting electrodes generating an output current having a fundamental frequency component when said beam is off-center, said transformer responding to said fundamental output current component for causing one of said pair of electron discharge devices to conduct more current

than the other for varying the biasing voltage on said resistor whereby the bias on said deflecting electrodes is varied to return said beam to a centered position.

12. An electron discharge device having means including a cathode means for directing electrons along a predetermined path, an output electrode for receiving said electrons, an interceptor element positioned between said cathode and said output electrode, deflecting electrodes positioned along the path of said electrons and on opposite sides thereof, means for applying an alternating voltage of a fundamental frequency to said deflecting electrodes for periodically deflecting said electron beam across said intercepting element to provide an output current having a second harmonic frequency, a circuit connected to said output electrode tuned to respond to an output current of the fundamental frequency of said alternating voltage, and a phase responsive rectifier biasing means connected with said deflecting electrodes and including a pair of electron discharge devices, said tuned circuit being coupled to said electron discharge devices for control thereof, the electron discharge device having deflecting electrodes generating an output current having a fundamental frequency component when said beam is off-center, said tuned circuit responding to said fundamental output current component for causing one of said electron discharge devices to conduct more current than the other for varying the biasing voltages on said deflecting electrodes to return said beam to a centered position.

13. An electron discharge device having means including a cathode means for directing electrons along a predetermined path, an output electrode for receiving said electrons, an interceptor element positioned between said cathode and said output electrode, deflecting electrodes positioned along the path of said electrons and on opposite sides thereof, means for applying an alternating voltage of a fundamental frequency to said deflecting electrodes for periodically deflecting said electron beam across said intercepting element to provide an output current having a second harmonic frequency, a circuit connected to said output electrode tuned to respond to an output current of the fundamental frequency of said alternating voltage, and a rectifier biasing means connected with said deflecting electrodes and including an electron discharge device, said tuned circuit being coupled to said electron discharge device for control thereof, the electron discharge device having deflecting electrodes generating an output current having a fundamental frequency component when said beam is off-center, said tuned circuit responding to said fundamental output current component for causing said electron discharge device to conduct varying amounts of current for varying the biasing voltage on said deflecting electrodes to return said beam to a centered position.

14. An electron discharge device having means including a cathode means for directing electrons along a predetermined path, an output electrode for receiving said electrons, an interceptor element positioned between said cathode and said output electrode, deflecting electrodes positioned along the path of said electrons and on opposite sides thereof, means for applying an alternating voltage of a fundamental frequency to said deflecting electrodes for periodically deflecting said electron beam across said intercepting element to provide an output current having a second har-

monic frequency, a circuit connected to said output electrode tuned to respond to an output current of the fundamental frequency of said alternating voltage, and biasing means connected between said deflecting electrodes and including a resistor, a pair of electron discharge devices each having a cathode, grid, and anode, the said anodes being connected to opposite ends of said resistor, said tuned circuit being coupled to said grids, and means including a transformer having a secondary the opposite ends of which are connected to the cathodes of said pair of electron discharge devices for applying an alternating voltage between said cathodes of the fundamental frequency of said alternating voltage applied to said deflecting electrodes, the electron discharge device having deflecting electrodes generating an output current having a fundamental frequency component when said beam is off-center, said tuned circuit responding to said fundamental frequency output current component for causing one of said pair of electron discharge devices to conduct more current than the other for varying the biasing voltage on said resistor whereby the bias on said deflecting electrodes is varied to return said beam to a centered position.

15. An electron discharge device having means including a cathode means for directing electrons along a predetermined path, an output electrode for receiving said electrons, an interceptor element positioned between said cathode and said output electrode, deflecting electrodes positioned along the path of said electrons and on opposite sides thereof, means for applying an alternating voltage of a fundamental frequency to said deflecting electrodes for periodically deflecting said electron beam across said intercepting element to provide an output current having a second harmonic frequency, a circuit connected to said output electrode tuned to respond to an output current of the fundamental frequency of said alternating voltage, and biasing means connected between said deflecting electrodes and including a resistor, a pair of electron discharge devices each having a cathode, grid, and anode, the said anodes being connected to opposite ends of said resistor, said tuned circuit being coupled to said grids, and means for applying an alternating voltage of said fundamental frequency between said cathodes and including an inductance, and a feedback coil connected between each anode of said pair of electron discharge devices and said resistor and coupled to said inductance, the electron discharge device having deflecting electrodes generating an output current having a fundamental frequency component when said beam is off-center, said tuned circuit responding to said output current component of fundamental frequency for causing one of said pair of electron discharge devices to conduct more current than the other for varying the biasing voltage on said resistor whereby the bias on said deflecting electrodes is varied to return said beam to a centered position.

16. An electron discharge device having means including a cathode means for directing electrons along a predetermined path, an output electrode for receiving said electrons, an interceptor element positioned between said cathode and said output electrode, deflecting electrodes positioned along the path of said electrons and on opposite sides thereof, means for applying an alternating voltage of a fundamental frequency to said deflecting electrodes for periodically deflecting said electron beam across said intercepting element to provide an output current hav-

ing a second harmonic frequency, a circuit connected to said output electrode tuned to respond to an output current of the fundamental frequency of said alternating voltage, and biasing means connected between said deflecting electrodes and including a resistor, a second resistor connected between said first resistor and said cathode means, a second electron discharge device having a cathode, grid, and anode, said anode being connected to one end of said first resistor, said tuned circuit being coupled to said grid, and means for applying an alternating voltage between the cathode and the anode of said second electron discharge device of the frequency of said alternating voltage applied to said deflecting electrodes, the electron discharge device having deflecting electrodes generating an output current having a fundamental frequency component when said beam is off-center, said tuned circuit responding to said output current component of fundamental frequency for causing said second electron discharge device to conduct varying amounts of currents for varying the biasing voltage on said resistor whereby the bias on said deflecting electrodes is varied to return said beam to a centered position.

17. A method of maintaining a beam of electrons centered in a beam deflection tube comprising applying an alternating deflecting voltage to said beam for causing said beam to be deflected periodically and equally on both sides of a predetermined mean path, causing said beam to generate an output current having a harmonic frequency of said deflecting voltage when said beam is properly centered and an output current component having a frequency corresponding to the frequency of said deflecting voltage when said beam is unequally deflected about said mean path, rectifying said output current of fundamental frequency, and utilizing said rectified current for providing a voltage bias for shifting said beam when said beam is off-center to maintain equal deflection of said beam about said predetermined path as a mean position.

18. The method of maintaining an electron beam in a beam tube centered along a predetermined path as a mean position in an electron discharge device having a transconductance characteristic passing successively through negative and positive values, comprising applying an alternating electric field to said beam for periodically deflecting said beam about said predetermined path, generating an output current having a frequency corresponding to a harmonic frequency of said deflecting voltage when said beam is properly centered and generating an output current component having a frequency corresponding to the frequency of said alternating electric field when said beam is off-center, said transconductance characteristic having a positive or negative value depending upon the phase relationship of said output current of fundamental frequency with respect to the phase of said alternating electric field, rectifying said output current of fundamental frequency for generating a biasing voltage, and applying said biasing voltage to said electron beam for returning said beam to a properly centered position.

19. The method of maintaining an electron beam centered along a predetermined path as a mean position in an electron discharge device provided with a source of electrons, a control electrode means and an output electrode and having a transconductance characteristic passing successively through negative and positive values

whereby the output current experiences a reversal of slope, and comprising the steps of applying biasing voltages to said electron discharge device for adjusting the device to a point of zero transconductance such that with varying voltages applied to said control electrode means the transconductance will vary periodically between equal negative and positive values when said beam is properly centered, said transconductance having higher positive values than negative values when said beam is off-center in one direction and having greater negative values than positive values when the beam is off-center in the other direction whereby an output current component having a frequency of the applied varying voltage is generated when said beam is off-center, rectifying said output current component for generating a biasing voltage and applying said biasing voltage to the control electrode means for returning said beam to a properly centered position.

20. The method of maintaining an electron beam centered along a predetermined path as a mean position in an electron discharge device provided with a source of electrons, a control electrode means and an output electrode and having an output current characteristic which increases on either side of a minimum value whereby the output current experiences a reversal of slope, comprising the steps of applying biasing voltages to said electron discharge device for adjusting the device to a point of minimum current such that with varying voltages applied to said control electrode means the output current will increase equally on both sides of said minimum current when said beam is properly centered, said output current having a higher value on one side than on the other of said minimum when said beam is off-center, whereby an output current component having a frequency of the applied varying voltage is generated when said beam is off-center, rectifying said output current component for generating a biasing voltage, and applying said biasing voltage to the control electrode means for returning said beam to a properly centered position.

21. An electron discharge device having means including a cathode for directing a beam of electrons along a predetermined path, an output electrode system in the path of said beam of electrons, and means positioned along the path of said electrons between said cathode and said output electrode system for deflecting said beam of electrons, means for applying an alternating voltage of a fundamental frequency to said deflecting means, said output electrode system generating an output current having a harmonic frequency of said fundamental frequency when said beam is properly centered along said predetermined path and generating an output current having a fundamental frequency component when said beam is deflected unequally on opposite sides of said predetermined path, means including a phase-responsive rectifier for applying a biasing voltage to said reflecting means for maintaining said beam centered along said predetermined path and means coupled to said output electrode system and responsive to an output current having a fundamental frequency component for controlling the phase-responsive rectifier circuit, the means coupled to said output electrode system having an output of one phase when said beam is off-center in one direction and having an output of an opposite phase when the beam is off-center in the other direction, said phase-respon-

sive rectifier varying the bias voltage in one direction to return said beam to a centered position in response to one phase and varying the bias voltage in the opposite direction when the phase is opposite.

22. An electron discharge device having means including a cathode for directing an electron beam along a predetermined path, electrode means in the path of said electrons, and deflecting electrode means along the path of said electrons between said cathode and the electrode means in the path of said electrons, means for applying a biasing voltage on said deflecting electrode means, means for maintaining said beam directed along said predetermined path when no deflecting voltage is applied to said deflecting electrode means, said electron discharge device having a transconductance characteristic passing successively through positive and negative values and having a zero transconductance value when the beam lies along its predetermined path, means for applying alternating voltage to said deflecting electrode means for periodically deflecting said electron beam about said predetermined path as a mean position, said transconductance characteristic having equal negative and positive values when said beam is properly centered and having a higher positive transconductance characteristic when the beam is off-center in one direction and having a higher negative value when the

beam is off-center in the opposite direction, and means responsive to the difference in values of said transconductance due to deviation of said beam from said path for varying the voltage applied by said biasing means in one direction when said beam is off-center in one direction and varying the voltage applied by said biasing means in the opposite direction when said beam is off-center in the opposite direction.
